(57) **CLAIM**

The ornamental design for a strap, as shown and described.

DESCRIPTION

FIG. 1 is a top, front, right side perspective view of a strap according to one embodiment of the invention;

FIG. 2 is a front elevational view of the embodiment of FIG.

1, the back elevational view being a mirror image thereof;

FIG. 3 is a left side elevational view of the embodiment of FIG. 1, the right side being a mirror image thereof;

FIG. 4 is a top plan view of the embodiment of FIG. 1, the bottom plan view being a mirror image thereof; and,

FIG. 5 is a top, front, right side perspective view of the strap of the embodiment of FIG. 1 in use with eyewear and in an expanded configuration.

The broken lines are for illustrative purposes only and form no part of the claimed design.
